UNITED STATES PATENT OFFICE.

CARLOS DYER, OF LEBANON, NEW HAMPSHIRE.

SLIDING DOOR.

SPECIFICATION forming part of Letters Patent No. 359,965, dated March 22, 1887.

Application filed September 25, 1886. Serial No. 214,535. (No model.)

To all whom it may concern:

Be it known that I, CARLOS DYER, a citizen of the United States, residing at Lebanon, in the county of Grafton and State of New Hampshire, 5 have invented certain new and useful Improvements in Sliding Doors; and I do declare the following to be a full, clear, and exact description of the invention, such as will enable others skilled in the art to which it appertains to make 10 and use the same, reference being had to the accompanying drawings, and to the letters and figures of reference marked thereon, which form a part of this specification.

The object of my invention is to so hang the 15 door on two single trucks that it will slide within a partition on a single track and require a pocket substantially no wider than the door is thick; also, to have the door-hanger adjustable and attached to a strip fastened to the top 20 of the door; also, to provide the inner edge of the door with rubber bunters of peculiar construction and adjustable; also, to stop the closing doors at the center without jar; also, to have the supporting-strip for the top casing removable, so that the truck may be easily repaired 25 or readjusted; also, to have the vertical studs and boards, which form the pocket and all parts around the door and truck so put together as to be easily taken apart.

30 My invention consists in details of construction, described below, and set forth in the claims.

In the drawings, Figure 1 is a side elevation in broken section, showing one door only, the 35 arrangement of the outer truck, and the removable parts, the inner truck being broken away with the door. Fig. 2 is a horizontal broken section near the top of the door, which is back in the pocket. Fig. 3 is a vertical broken section, chiefly showing the parts above the door. Fig. 4 is a side elevation, broken away, showing the lower rubber bunter on the inner edge 40 of the door. Fig. 5 is a plan view, broken away, showing the manner of stopping double doors at the center. Fig. 6 is an end elevation of the truck and bed removed.

Like letters refer to like parts.

a represents the door, and *b* the casing. To the top of the door is strongly fastened a strip, 50 *c*, of wood or metal, (see Figs. 1 and 3,) and to the jambs *d* is attached rubber friction-strips

e, for preventing rattling and undue lateral movement of the doors. To the strip *c*, a little back of the outer edge of the door, is attached the door-hanger *f*. The lower portion of it has 55 slots *c'*, provided with set screws *c''*, whereby the door may be adjusted when out of true hang. The strip *c* is very important, as the hanger is attached and adjusted upon it alone, and the wood-work of the door proper is not 60 cut into at all, as is the case where long screw arms or rods and a turn-wheel are used to adjust; furthermore, my construction does not render it necessary to bring long hanger-arms down upon the outside of the door; also, by the 65 use of said strip the top of the door is brought so near the track as to prevent any running off. The sheave *g* is journaled by a steel pin, *t*, in the upper part of the hanger, the slot *f'* being horizontally long, for the purpose of lateral adjustment if a change in either becomes necessary. The track *h*, which may be of rubber to deaden the sound, or of any suitable material, is oval, and is attached to a bed, *h'*, 70 strongly bolted to one of the strips *i i'*, (see 75 Fig. 3,) which are fastened to the vertical side studs, *n*, and the boards *m m*. One of these strips—for example, *i'*—should be left off until the door is hung, and both are easily removable, making it convenient to repair or readjust 80 the sheave or hanger. The beam *k* above the sheave should be as wide as the door-pocket.

l l' is a ground for the lath and plaster *l'*. *l'* and *m m* are also boards on either side of *k*.

The door-pocket is formed by the vertical 85 studs *n* and the boards *o*, *o'*, *o''*, and *o'''*, all of which, except *o'''*, are united by tongue-and-groove joints. (See Figs. 1 and 2.) This construction dispenses with the use of nails, and allows the pocket to be quickly set up, and in 90 view of the method of hanging the door the pocket need not be substantially wider than the thickness of the door. In double doors the other pocket would simply be a reversed construction of the one shown.

At two suitable points on the inner edge of the door, near the top and bottom, there are arranged two hollow rubber bunters, *p*, which strike the furring *o'''*, when the doors are run back and relieve the hangers from strain and 100 jar. Each bunter rests on a disk, *p'*, within the door, and back of this is a spiral spring, *p''*,

adjusted by means of said disk and a set-screw, p^3 , so that the bunter at the top will strike at the same time.

The manner of stopping double doors at the center without jar (see Fig. 5) is as follows: A strip or stop, r , having sides shod with rubber at $r' r'$, and being of the same thickness as the strip c on the top of the door, is fastened transversely on the bottom of the removable strips i i' . The strips $c c$, coming together with the doors, (but not being as long as the door top,) will strike against the rubber sides $r' r'$ and stop the door, the tongue s on one door having meanwhile entered the groove s' in the other. Where a single door is used, it is only necessary to put a rubber tip, x , on the end of strip c . (See Fig. 1.)

I do not deem it necessary to show both bunters p in one view, as they are separately shown in Figs. 2 and 4; nor do I deem it necessary to show both trucks or double doors in position, as the description of one will enable any one skilled in the art to properly arrange two. Care should be taken, however, to arrange the inner truck so as to exactly correspond oppositely to the location of the one shown.

It will be seen that by properly locating the single trucks the door or doors may be run back and not require a pocket wider than the door, and four sheaves and a single track will answer for double doors.

By making all the parts about the door and pocket removable great convenience and saving of labor are gained when readjustment or repairs are required, and by the mode of hanging at the top of the door it runs so near the track as to prevent running off.

Having fully described my invention, what I desire to claim and secure by Letters Patent is—

1. The combination, with the oval rubber track h , of the sheaves g , having pint, the hangers f , provided with lateral slot f' , vertical slots c' , and set screw c^2 , the strip c , and the door a , as set forth.
  2. The combination, with the door, the sheave-hangers, the sheaves, and their single track, of the removable furring i' , as set forth.
  3. The combination, with the furring i , of the track-bed h' , bolted thereto, the track h , the sheaves, and adjustable hangers $g f$, the removable furring i' , the door a , and its top strip, c , as set forth.
  4. The combination, with a sliding door hung substantially as shown, of the removable supporting-strip for the top casing, the beam k , the boards $m m$, and the ground l for the lath and plaster $l' l''$, as set forth.
  5. The combination, with the inner end of the door, of the rubber bunters, consisting of the hollow rubber portion p , the disk p' , the spring p^2 , and the set-screw p^3 , as set forth.
  6. The combination, with the removable furring $i i'$, of the transverse strip r , having rubber sides $r' r'$, and the doors $a a$, provided with top strips, $c c$, adapted to strike against the rubber sides $r' r'$ when the doors meet at the center, as set forth.
- In testimony whereof I affix my signature in presence of two witnesses.
- CARLOS DYER.
